(21) Appl. No.: **29/853,614**

(74) Attorney, Agent, or Firm — Barnes & Thornburg LLP

(22) Filed: **Sep. 16, 2022**

(57) **CLAIM**

(51) LOC (15) Cl. **24-02**

The ornamental design for an orthopaedic surgical reference instrument, as shown and described.

(52) U.S. Cl.

DESCRIPTION

USPC **D24/140**

(58) **Field of Classification Search**

FIG. 1 is a top perspective view showing the orthopaedic surgical reference instrument;

USPC D24/140, 133, 135, 155, 171
CPC A61F 2/4657; A61F 2002/4658; A61F 2002/4661; A61F 2002/4662

FIG. 2 is a bottom perspective view of the orthopaedic surgical reference instrument of FIG. 1;

See application file for complete search history.

FIG. 3 is a bottom plan view of the orthopaedic surgical reference instrument of FIG. 1;

(56) **References Cited**

FIG. 4 is a top plan view of the orthopaedic surgical reference instrument of FIG. 1;

U.S. PATENT DOCUMENTS

FIG. 5 is a first side elevation view of the orthopaedic surgical reference instrument of FIG. 1;
